UNITED STATES PATENT OFFICE.

STEPHEN S. NEWTON, OF BINGHAMTON, NEW YORK.

BOTTLE-STOPPER.

SPECIFICATION forming part of Letters Patent No. 251,923, dated January 3, 1882.

Application filed June 23, 1881. (Model.)

To all whom it may concern:

Be it known that I, STEPHEN S. NEWTON, a citizen of the United States, residing at Binghamton, in the county of Broome and State 5 of New York, have invented certain new and useful Improvements in Bottle-Stoppers; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

Figure 1 is a vertical section of my improved 15 stopper. Fig. 2 is a vertical section, showing a part of the invention. Fig. 3 is a section of my stopper having a vent-tube applied thereto. Fig. 4 is a vertical section of Fig. 2 enlarged. Fig. 5 is a plan or top view of Figs. 2, 3, 4, with 20 ports closed. Fig. 6 is a horizontal section taken on line *y y*, Fig. 3. Fig. 7 is a horizontal section taken on line *x x*, Fig. 1.

In all the figures, *F* is a discharge-tube, through which the contents of the bottle are 25 delivered, its upper end being closed by a flat plate provided with one or more eccentric ports, *f*.

In Fig. 1 the lower end of the discharge-tube is screw-threaded externally to receive a cork, 30 *D*, and has a horizontal flange, *B*, adapted to cover the bottle-neck. In the other figures the tube *F* is screw-threaded internally to engage with an external screw-thread on the bottle-neck.

F' is a cap-plate fitting closely upon the flat 35 upper surface of the discharge-tube, and is provided with a downwardly-projecting flange, *C*, which fits closely the outer surface of the discharge-tube, and with eccentric ports *f'*. The 40 rotation of the cap-plate is limited as follows: *e* is a spur projecting from the inner face of the depending flange *C* and entering a groove or recess, *g*, formed for its reception in the discharge-tube, near its upper edge, so that when 45 the spur *e* strikes the vertical wall at either end of the slot further rotation of the cap-plate in the direction in which it is then moved is checked, the relation of the groove and spur to the ports *f f'* being such that when the cap- 50 plate has reached the limit of its rotation in one direction these ports will coincide, as in

Figs. 1, 2, 3, 4, and that when it has reached the limit of its throw in the opposite direction the ports shall not coincide, as indicated in dotted lines, Fig. 5.

In Fig. 1 the spur *e* and groove *g* perform the further function of holding the cap-plate and its flange down closely upon the upper flat end of the discharge-tube, this result being accomplished in the other figures by reason of the lower edge of the flange *C* being spun or otherwise turned in under a bead formed upon the upper end of said tube, the spur *e* being formed, by preference, in all the figures by a blow with a punch.

In each of the other constructions (represented by Figs. 2, 4, 6, 7) the upper end of the discharge-tube has a projecting rib or bead, the cap-plate being secured to the upper face of the flat tube-plate by means of a depending flange, 60 the lower edge of which is spun under the lower edge of the said bead or rib, thus forming a groove in which the said bead or rib is seated.

From an examination of the drawings it will be seen that in each of the constructions shown 75 the cap-plate is attached to the upper face of the tube-plate by means of a groove and a projection which enters the groove and engages with its walls.

In Fig. 4, *G* is a vent-tube attached to the 80 lower side of the upper end of the discharge-tube and opening into one of the ports *f*, so that the vent-tube and the discharge-port *f* shown in Fig. 4 shall be opened and closed simultaneously by the rotation of the cap-plate.

I am aware that bottle-stoppers have been constructed with eccentric ports at the upper 85 ends of their discharge-tubes, and with rotating plates having corresponding eccentric ports and stops to limit the rotation of said plates; 90 but I believe I am the first to construct a bottle-stopper containing a flat plate covering the upper end of the discharging-tube, a cap-plate resting upon the upper face of said tube-plate, a flange depending from the outer edge of the 95 cap-plate and secured to the tube by means of a groove and a projection entering said groove, the two plates being provided with eccentric ports and a stop to limit the rotation of the cap-plate.

What I claim is—

1. In a bottle-stopper, a discharge-tube hav-

ing at its upper end a flat circular plate provided with an eccentric port, in combination with a cap-plate having an eccentric port, and a downwardly-projecting flange mounted upon and secured to the upper face of the tube-plate by means of a groove and a projection which engages with the groove, and a stop which limits the rotation of the cap-plate, substantially as set forth.

10 2. In a bottle-stopper, a discharge-tube having at its upper end a flat circular plate, an eccentric port, and an eccentric vent-tube, in combination with a cap-plate having two eccentric ports,

and a downwardly-projecting flange mounted upon and secured to the upper face of the tube-plate by means of a groove and a projection which engages with the groove, and a stop which limits the rotation of the cap-plate, substantially as set forth. 15

In testimony whereof I affix my signature in presence of two witnesses.

STEPHEN S. NEWTON.
